UNITED STATES PATENT OFFICE.

JOHN A. MADDOX, OF WEST UNION, OHIO, ASSIGNOR, BY DIRECT AND MESNE ASSIGNMENTS, OF TWO-THIRDS TO M. A. LITTLE AND WILLIAM COOPER, OF SAME PLACE.

CHURN.

SPECIFICATION forming part of Letters Patent No. 531,204, dated December 18, 1894.

Application filed August 14, 1894. Serial No. 520,317. (No model.)

To all whom it may concern:

Be it known that I, JOHN A. MADDOX, a citizen of the United States, residing at West Union, in the county of Adams and State of Ohio, have invented a new and useful Churn, of which the following is a specification.

The invention relates to improvements in churns.

The object of the present invention is to improve the construction of churning, and to provide a simple and comparatively inexpensive one, capable of rapidly producing butter, and adapted, after the operation of churning is completed, to separate the butter, and to elevate the same to the top of the churn, to facilitate its ready removal from the churn body.

The invention consists in the construction and novel combination and arrangement of parts hereinafter fully described, illustrated in the accompanying drawings and pointed out in the claims hereto appended.

In the drawings: Figure 1 is a perspective view of a churn constructed in accordance with this invention, the dasher and the butter lifting receptacle being elevated. Fig. 2 is a central vertical sectional view of the same, the parts being in position for churning. Fig. 3 is a detail perspective view illustrating the manner of detachably swiveling the butter lifting receptacle to the lower end of the dasher shaft. Fig. 4 is a detail sectional view of one side of the churn, illustrating the construction of the slides and the ways.

Like numerals of reference indicate corresponding parts in all the figures of the drawings.

1 designates a rectangular churn body, provided with legs 2 and having a cover 3, connected with the body by opposite depending slides 4 arranged in vertical ways 5 of the body. The ways 5 are preferably formed by vertical grooves covered by strips 6 of sheet metal, or the like; and when the churn is open the cover is elevated, and the slides are moved vertically in their ways, by means hereinafter described.

The cover 3 is provided with a hinged sec-

tion 7 to permit access to the interior of the churn without elevating the cover; and it has a central opening in which is journaled a vertically disposed dasher shaft 8, depending from the cover and carried by the same and provided with oppositely disposed vertically arranged perforated dasher blades 9. The dasher blades 9 are rotated in the body to effect the operation of churning; and the dasher shaft is extended upward through the cover 3, and is provided with a collar 10, located upon the upper face of the cover.

The upper end of the dasher shaft is provided with a horizontally disposed bevel pinion 11, which meshes with a bevel gear wheel 12, carried by a swinging frame 13 and adapted to mesh with the bevel pinion, as illustrated in Fig. 2 of the accompanying drawings, when the swinging frame is in a vertical position.

The swinging frame is hinged at its bottom to one side of the churn body. It may be of any desired construction; and it is provided at its top with a bearing 14, in which is journaled a drive shaft 15, carrying a crank wheel 16 at one end and having the beveled gear wheel 12 at its other. This frame 13, which may be provided with arms 17 is connected at opposite sides by cords 18, or the like, which are arranged in horizontal grooves 19 at the upper edges of the churn body, and which pass over the pulleys 20 at the inner terminals of the grooves, and are secured at their lower or inner ends to the bottoms of the vertical slides 4. When the frame 13 is swung downward, it draws the cords, which are attached to the ends of the arms 17, outward, and thereby carries the slides upward and elevates the cover and the dasher mechanism carried by the same. As the swinging frame is moved upward and inward to its normal vertical position, the cover and the dasher mechanism descend within the churn body.

A rectangular receptacle or strainer 21 is detachably swiveled to the lower end of the dasher rod, and is carried by the cover 3 in its upward movement; and it conforms to the configuration of the churn body, and strains and collects the butter, and conveys the same to the top of the churn body. The receptacle

or strainer is provided at its bottom with perforations, and has sides or flanges; and it is provided with a centrally arranged vertically disposed sleeve 22, receiving the lower portion of the dasher shaft and provided at its top with an annular flange. The lower end of the dasher shaft is reduced to form a shoulder 24, against which the flange 23 bears; and the sleeve is detachably swiveled to the shaft 10 by a pivoted catch 25. The pivoted catch 25 consists of a stem and a horizontal arm 26, arranged at the bottom of the stem, and provided intermediate of its ends with a semi-circular bend, which engages the sleeve below 15 the flange thereof, and thereby holds the sleeve on the shaft. The adjacent inner edges of the blades are recessed to clear the pivoted catch; and the stem of the latter is provided intermediate of its ends with an eye to receive 20 the pivot 27. After the butter has been separated and strained, it is conveyed to the top of the churn body by the rectangular receptacle or strainer, from which the butter may be readily removed; and the butter lifting 25 receptacle or strainer may be detached if desired.

The slides 4 are provided at one edge, adjacent to the cord, with a groove 28 to receive the same, and to prevent the cord from being 30 unnecessarily worn by friction. The churn body is provided at one side, near its bottom, with a discharge opening 29, and it has a spout 30; and during the operation of churning a plug 31 is fitted in the discharge opening. 35

The legs 2 may consist of strips of metal secured to the bottom of the churn body and having their terminals bent downward and outward at a slight inclination, as shown. 40 The swinging frame is provided at its bottom with a hinge leaf secured to the churn body and connected with the upper portion of the frame by a pintle.

It will be seen that the churn is simple and 45 comparatively inexpensive in construction, that it is adapted to produce butter rapidly, and that after the operation of churning has been completed, the butter is readily separated, strained, and conveyed to the top of 50 the churn body to facilitate its removal.

Changes in the form, proportion, and the minor details of construction may be resorted to without departing from the principle or sacrificing any of the advantages of this invention. 55

What I claim is—

1. In a churn, the combination of a churn body, a vertically movable cover connected with the body, dasher mechanism connected 60 with the cover, a butter receptacle carried by the same, a swinging lever frame connected with the cover and mounted on the churn body and adapted to elevate the cover, substantially as described.
2. In a churn, the combination of a churn body, a cover provided with slides mounted on the body and capable of vertical move- 65

ment, dasher mechanism carried by the cover, a swinging frame mounted on the body and carrying gearing for operating the dasher mechanism, and the flexible connections between the frame and the slides, whereby the cover and the dasher mechanism are elevated when the frame is swung away from the churn body, substantially as described. 75

3. In a churn, the combination of a churn body, a cover provided with slides mounted on the churn body, the butter lifter and strainer connected with and carried by the cover, and the swinging frame mounted on the churn body and connected with the slides, substantially as and for the purpose described. 80

4. In a churn, the combination of a churn body provided with ways, a cover having depending slides arranged in the ways of the body, dasher mechanism mounted on the cover, a swinging frame hinged to the churn body and carrying gearing for operating the dasher mechanism, and the cords extending from the frame to the slides and connected with the lower ends of the latter, substantially 90 as described.

5. In a churn, the combination of a churn body provided with ways and having grooves at its upper edges, pulleys located at the inner terminals of the grooves and located adjacent to the ways, grooved slides mounted in the ways, a swinging frame hinged to the churn body, the cords arranged at opposite sides of the churn body and secured to the frame and arranged in said grooves and connected to the slides at the bottom thereof and fitting in the grooves of the same, and dasher mechanism carried by the cover, substantially as described. 95 100 105

6. In a churn, the combination of a churn body, a cover provided with slides mounted on the body, a swinging frame hinged to the churn body and connected with the slides, a dasher shaft journaled on the cover and depending therefrom and provided with blades, gearing carried by the frame for rotating the dasher shaft, and a butter lifting receptacle conforming to the configuration of the churn body and connected with the lower end of the shaft and carried by the same, substantially 110 115 as described.

7. In a churn, the combination of a churn body, a cover provided with slides mounted on the body, a swinging frame hinged to the churn body and connected with a slide, a dasher depending from the cover, a receptacle arranged at the bottom of the dasher and detachably swiveled to the same, substantially as described. 120 125

8. In a churn, the combination of a churn body, a cover provided with slides mounted on the body, a swinging frame hinged to the body and connected with the slides, a dasher shaft depending from the cover, a receptacle conforming to the configuration of the churn body and provided with an upward extending sleeve receiving the lower end of the shaft and having a flange, and a pivoted catch 130

mounted on the shaft and having an arm provided with a curved portion conforming to the configuration of the sleeve and engaging the same below the flange thereof, substantially as described.

9. In a churn, the combination of a churn body, a cover provided with slides mounted on the body, a dasher having a shaft journaled on the cover and extending above the same, a pinion arranged at the upper end of the dasher shaft, a swinging frame mounted on the churn body and connected with said slide and provided with a bearing, a shaft journaled in the bearing and having a crank handle at its outer end, and a gear wheel arranged at the inner end of the last mentioned shaft and arranged to mesh with the pinion of the dasher shaft when the swinging frame is in a vertical position, substantially as described.

10. In a churn, the combination of a churn

body, a cover provided with slides mounted on the churn body, a swinging frame hinged to the churn body and connected with the slides, a dasher shaft provided with blades 25 and journaled on the cover and extending above and below the same, a perforated receptacle detachably swiveled to the lower end of the dasher shaft, a pinion fixed to the upper end of the dasher shaft, and a drive shaft 30 journaled on the swinging frame and carrying a gear wheel arranged to mesh with the pinion, when the frame is in an upright position, substantially as described.

In testimony that I claim the foregoing as 35 my own I have hereto affixed my signature in the presence of two witnesses.

JOHN A. MADDOX.
